(57) **CLAIM**

The ornamental design for a tire tread of a vehicle tire, as shown and described.

DESCRIPTION

FIG. 1 is a perspective view of the vehicle tire, showing my new design;

FIG. 2 is a front elevational view thereof;

FIG. 3 is an enlarged partial front view thereof; and,

FIG. 4 is a right side elevational view thereof of which the left side is a mirror image thereof.

The dash-dot lines in FIG. 3 showing the boundaries of the illustrated detail form no part of the claimed design.

In the drawings, the broken lines defining the sidewall, and inner bead depict environmental subject matter that forms no part of the claimed design.
